UNITED STATES PATENT OFFICE

2,647,358

CENTRIFUGAL METHOD FOR THE WET SPINNING OF NATURAL FIBERS AND APPARATUS FOR CARRYING OUT THIS METHOD

Aldo Bolelli, Bologna, Italy

Application March 5, 1951, Serial No. 213,832
In Italy December 27, 1950

3 Claims. (Cl. 57—76)

1

This invention relates to improvements in apparatus for wet centrifugal spinning of natural fibers disclosed in my co-pending patent application Serial No. 186,092, filed September 26, 1950.

It is an object of the present invention to provide means for holding the yarn holder in its uppermost position reached during the reciprocation, at the moment that the apparatus is stopped.

It is another object of this invention to provide a container for the annulus of the yarn spun having the wall perforated with a plurality of holes and which follows the annulus during the drying thereof.

It is a further object of the invention to provide means for winding the collected yarn into hanks.

With these and other objects in view, as will appear from the following description and drawings, the invention consists in the novel features of construction, combination of elements and arrangement of parts hereinafter to be fully described.

A preferred embodiment of the apparatus is illustrated in the accompanying drawing wherein:

Figure 1 is a diagrammatic lateral view of the yarn holder operating means;

Figure 2 is a detailed front view of the means for stopping the yarn holder in its uppermost position;

Figure 3 is a perspective view of the annulus of yarn spun, and

Figure 4 is a diagrammatic lateral elevational view of the means for winding the collected yarn into hanks.

Referring to Figures 1 and 2, the reference 1 indicates a disc fixed to the shaft 15 whereon at least one pulley is mounted, which operates the supporting rods 20 for the yarn holders 19. On the periphery of disc 1 a notch 21 is provided (Figure 3) wherein a pawl 2 may engage and which pawl is elastically mounted by means of spring 18 on the end of shaft 23 which is controlled by hand lever 3. When pawl 2 engages notch 21, the disc 1 may be stopped when rod 20 and yarn holder 19 are in their uppermost position.

The disc 1 is put in motion by the heart-shaped cam 12 through lever 13 and the flexible and inextensible member 14 which may be formed for example by chain. On shaft 15 at least one pulley 17 is mounted on which the chain 16 winds up, and chain 16 controls a relative rod 20.

To stop the apparatus, lever 3 is moved so as to cause, through spring 18, the pawl 2 to en-

2

gage notch 21 of the disc 1. Since the lowering of the rod 20 and yarn holder 19 therewith takes place due to gravity, the heart-shaped cam 12 may continue to rotate without affecting yarn holder 19 which is stopped in its uppermost position. When the apparatus is again started, lever 3 is re-set in the home position and pawl 2, always through spring 18 is moved from disc 1, thus permitting the latter, rod 20 and yarn holder 19 to be moved.

The annulus of yarn is spun inside the container 11 (Figure 3) which is formed as a cylinder having a bottom with a central bore, a side wall perforated with a plurality of holes and with the upper part bent inwardly so as to generate a central bore wherein the yarn holder penetrates. By using this container it is no longer necessary, as in the apparatus disclosed in my copending application, to remove the annulus from the container to subject the annulus to drying; on the contrary, the annulus on drying remains in the container and the holes existing in the side wall thereof facilitates the drying.

After the drying of the annulus is effected, the collected yarn is wound into hanks by means of the device illustrated in Figure 4. The device includes a bracket 4 fixed to the lateral frame 5 of the apparatus. On the bracket, a plurality of spindles 6 are fixed having a cylindrical lower portion and a conical upper portion. Above each spindle there is mounted a yarn-guide 7 provided with a hole in line with the axis of spindle 6 and hinged to a support 8 fixed to the lateral frame 5 of the apparatus. A second yarn-guide 9, disposed above yarn guide 7, serves to distribute the yarn over the reel 24.

Container 11 with the annulus is placed on spindle 6 and arranged in the annular seat 10 on the bracket 4. Obviously the inner bore of the annulus has to be greater than the outer diameter of spindle 6. For unwinding the annulus, the free end of the yarn is passed through the holes of yarn guides 7 and 9 and then brought to the reel 24. On winding the yarn into hanks 45 the yarn at the outlet of the container 11 is caused to rapidly rotate so as to assume the shape of a double spindle as shown in dotted line in Figure 4. Spindle 6 has the purpose of preventing entangling of the yarn during the unwinding 50 thereof from the annulus.

I claim:

1. In apparatus for wet centrifugal spinning of natural fibers, a vessel rotatable round its axis wherein the annulus of yarn spun is formed, a 55 yarn holder movable in a vertical direction up,

wardly, a cam controlled shaft for moving said yarn holder upwardly, said yarn holder and shaft being movable downwardly by gravity to return to the initial position, and means manually operable for holding said yarn holder in the uppermost position when the apparatus is stopped.

2. In apparatus for wet centrifugal spinning of natural fibers, the combination of a vessel rotatable around its horizontal axis and wherein an annulus of yarn is formed, a yarn holder extending into said vessel, a heart-shaped cam operable to move upwardly said yarn holder, said yarn holder being movable downwardly by gravity, a vertical rod supporting said yarn holder and movable upwardly and downwardly therewith, a disc rotatably mounted on a horizontal shaft, a pulley mounted on the said horizontal shaft, flexible transmission means adapted to wind up said pulley and connected to said vertical rod, said heart-shaped cam being rotatable around a horizontal shaft, an oscillating lever controlled by said heart-shaped cam and adapted to transmit the rotating motion to said disc, said disc having a notch formed in the periphery thereof, a pawl engageable with said notch to stop the disc, a hand operated lever, elastic means connecting said lever to said pawl, said pawl being manually operable through said lever and said elastic means to selectively hold the yarn holder in the uppermost position when the apparatus is stopped.

3. In apparatus for wet centrifugal spinning of natural fibers the combination of a vessel rotatable around its axis, a container introduced in said vessel and rotatable therewith and adapted to receive an annulus of yarn formed

during the centrifugal spinning, said container being formed with a bottom axially bored, a side perforated with a plurality of holes, the top of the side wall being bent inwardly so as to generate a central bore, a yarn holder extending inside said container and adapted to move upwardly and downwardly, a vertical rod supporting said yarn holder and movable upwardly and downwardly therewith, a disc rotatable around a horizontal shaft, a pulley mounted on said horizontal shaft, flexible transmission means adapted to wind up said pulley and connected to said vertical rod, a heart-shaped cam rotatable around a horizontal shaft, an oscillating lever controlled by said heart-shaped cam to transmit the rotating motion to said disc, said disc having a notch provided on the periphery thereof, a pawl engageable with said notch to stop the disc, a hand operated lever, elastic means connecting said lever to said pawl, said pawl being manually operable through said lever and said elastic means to selectively hold the yarn holder in the uppermost position when the apparatus is stopped.

ALDO BOLELLI.
